Primary Examiner — Cynthia M Chin(74) *Attorney, Agent, or Firm* — Livingston Loeffler, P.A.;
 Edward M. Livingston, Esq.; Bryan L. Loeffler, Esq.(57) **CLAIM**

The ornamental design for a two wheeled recreational board, as shown and described.

DESCRIPTION

FIG. 1 is a top perspective view of a two wheeled recreational board of the present invention;

FIG. 2 is a front view of the two wheeled recreational board of the present invention;

FIG. 3 is a rear view of the two wheeled recreational board of the present invention;

FIG. 4 is a top view of the two wheeled recreational board of the present invention;

FIG. 5 is a bottom view of the two wheeled recreational board of the present invention;

FIG. 6 is a left side view of the two wheeled recreational board of the present invention; and,

FIG. 7 is a right side view of the two wheeled recreational board of the present invention.
